UNITED STATES PATENT OFFICE.

OLAV ESKIL JORGENSEN, OF FOREST HILLS, NEW YORK, ASSIGNOR TO WORTHINGTON PUMP AND MACHINERY CORPORATION, OF NEW YORK, N. Y., A CORPORATION OF VIRGINIA.

INTERNAL-COMBUSTION ENGINE.

Application filed December 3, 1924. Serial No. 753,593.

This invention relates to improvements in internal combustion engines, and particularly to engines of the Diesel or similar oil-burning type.

5 The object of the invention is to provide an improved construction of cylinder, especially adapted for double-acting engines of the two-cycle type and particularly suitable for heavy power purposes, as, for example, 10 marine engines, the construction being such as to be of great strength but light weight and secure proper alignment and durability with efficient cooling of the parts, while the various parts of the engine may readily be 15 assembled and disassembled.

With these objects in view, the invention consists in various features of construction and combinations of parts which will be first described in connection with the accompanying 20 drawings, showing a double-acting engine of the preferred form embodying the invention, and the features forming the invention then be specifically pointed out in the claims.

25 In the drawings—

Figure 1 is a vertical section of the engine cylinder and piston;

Figures 2, 3 and 4 are cross-sections on, respectively, the lines 2—2, 3—3 and 4—4 30 of Fig. 1;

Figure 5 is a longitudinal section of one-half of the piston, on the line 5—5 of Fig. 3.

The engine shown is that of my pending application for United States Letters Patent 35 Serial No. 537,136, filed February 16, 1922, including certain improvements on the construction described and claimed in that application, although many of the features are applicable also to engines of other types.

40 Referring to the drawings, A is a casting mounted on engine frame B and forming a center piece or cylinder base on which the cylinders of the double-acting engine shown are mounted. This cylinder base A has

45 formed therein the scavenging ports 10 and exhaust ports 11 connecting, respectively, with the scavenging manifold C and exhaust manifold D, and this cylinder base also contains the cooling liquid chambers 12 forming

50 a part of the cylinder cooling water circulation, and has a heavy central diaphragm 13 provided with a shoulder 14 which extends inwardly to form a firm seating for the cylinders.

55 The cylinders are formed with cylinder

liners 15 having heavy shoulders by which they are seated on shoulder 14 of the base A, and the two liners for the respective cylinders of the double-acting engine preferably are provided with overlapping portions 1 at 60 their base ends forming a continuous running surface for the piston, except for the joint between the ends of the portions 1. These liners extend at their outer ends beyond the piston movement and are seated 65 against shoulders formed on the cylinders 16, which cylinders are formed with thickened bases 17 at their inner ends by which they are seated on shoulders on the liners and guided and held between the liners and 70 the inner wall of base A, so that perfect alignment and firm mounting of the cylinders is secured and maintained, all joints being metal to metal. The liners are held to the cylinder base at their inner ends, that is, 75 the ends where they meet, and thereby the expansion of each liner is in the direction from its inner end toward its outer end. Therefore, as the overlapping portion 1 of 80 one liner is relatively short and its expansion negligible, the two liners meeting and overlapping at their inner ends constitute a continuous liner device extending throughout the entire piston travel, and the joint between the liners over which the piston must pass is maintained so tight that there is no 85 chance of the piston rings scoring the liners at the said joint. The cylinder ends are preferably of the special dome form shown, formed in two zones, the zone next to the 90 cylindrical body portion of the cylinder preferably being spherical and the remainder of the dome a conoidal dome tangent to the spherical portion, but it will be understood that this form is not essential to the 95 present invention. The outer cylinder 16 is closed at the top by cap 19 through which is mounted the central fuel spray valve a, and the cylinder 16 at the inner or piston rod end is closed by cap 20, in which the piston rod 100 is packed, and in the opposite sides of the cylinder wall are preferably mounted two fuel valves a', a'', so as to properly distribute the fuel supply on opposite sides of the piston, which is formed at the end to provide 105 suitable combustion chambers on opposite sides of the piston. The cylinders 16 and liners 15 are clamped together against the shoulders 14 on base A, so as to hold these parts firmly in aligned position by heavy 110

clamping rings 21 bolted to the base A, and within these clamping rings are the cooling jackets 22 surrounding the cylinder ends with stuffing boxes 2 between them and the clamping rings, these cylinder jackets being supported at their outer ends by bolting on the respective cylinder heads 19, 20. These jackets, therefore, are removable as a unit with the cylinders and may readily be removed from the cylinders. The inner ends of the jackets being free, expansion and contraction of the jackets is provided for, while leakage is prevented by the packing 2.

The cooling water circulation for the cylinders and liners is as follows: The cooling chambers 12 are connected at opposite sides by side chambers 24, into one of which cooling water is admitted through port 23, as shown in Fig. 2, and from these cooling chambers 12 the water passes through vertical passages 3 and horizontal passages 4 to passages 5 formed in the liner and cylinder walls, and thus flows within the clamping ring 21 and through helical passages 6 formed between the jackets 22 and cylinder 16 to the jacket chambers 25, 25, at the outer ends of the cylinders. The entire cylinder, liner, and port construction thus is efficiently cooled.

30 The piston rod E supports directly all parts of the piston construction so that a firm and efficient support of all parts is secured. A heavy center piece 26 is mounted on the rod between the two pistons, preferably by a rib and groove mounting 7, as shown, so that this center piece forms a rigid running member within the liners and between the pistons. This center piece is split into halves for convenient application, 35 the halves being secured together by bolts, as shown in Fig. 3. On opposite sides of the center piece 26 the piston rod carries enlargements or heads integrally formed therewith. At the upper end of the piston rod 40 two heads 27 are formed so as to provide for water circulation within the piston about the smaller portion of the rod between the heads, and the upper piston head 28 is seated upon the head 27, with the cylindrical portion of 45 the upper piston 30 that carries the piston rings sliding on the lower head 27 with packing to prevent leakage, expansion and contraction of the piston thus being provided for. The lower piston rod enlargement or 50 head 29 has the piston head 28 seated on its end with the cylindrical portion 30 free to slide in packing on the enlargement 29, as in the case of the upper piston. The upper and lower pistons are secured to the piston rod 55 heads or enlargements by bolts 32, extending from the inner side of the piston rod heads into the piston heads 28, as shown in Fig. 5, the whole piston construction, with center piece 26, thus forming a single unit firmly 60 mounted upon the piston rod.

The piston cooling liquid is supplied in any suitable manner and passes upward through the annular space about the tube 31 within the piston rod E, and from this space through the lower side passages 8, on one side of a diaphragm in the space in piston rod enlargement or head 29, to the interior of piston 30, so as to circulate within the piston head and behind the running portion and piston rings, and then through 75 the upper side passages 8 in said piston rod, head 29 on the opposite side of the diaphragm to the space about tube 31 and through side passages 9 to the interior of the upper piston portion 30 and within its 80 piston head 28, circulating throughout the piston and within the running portion and piston rings and then through passages 9' to the under side of the top of the piston, returning through the tube 31. The whole 85 piston, including the piston heads and the running portion carrying the piston rings, are thus efficiently cooled, each piston having its own circulation.

It will be obvious that by the construction 90 of the piston as described, a light yet very strong piston is produced, which may be readily assembled and disassembled, while the piston is efficiently cooled and any longitudinal expansion or contraction of the piston 95 due to temperature changes, is fully provided for. In disassembling the piston, it is necessary only to remove the entire double-acting piston and piston rod from the cylinder, take off the split center piece 26 and then, by removal of the bolts 32, each of the pistons may readily be removed and the parts disassembled. The cylinders also are 100 readily assembled and disassembled, the cylinders with their respective liner and jackets 105 being removable as units, when released by the removal of the clamps 21, and the liners, jackets, and cylinder heads then being readily disassembled.

While in the foregoing specification the 110 invention has been more particularly shown and described as embodied in a vertical engine, it is to be understood that the invention is applicable to horizontal or inclined engines, and that the terms "upper" and "lower", referring to the cylinders and pistons, are to be understood as including cylinders and pistons which are not above and below each other, but nearest to or farthest 115 from the crank shaft.

It will be understood, also, that the invention is not limited to double-acting engines, but that certain features are applicable to single-acting engines and are thus claimed, although the invention is especially intended 125 for double-acting engines and certain features and combinations of parts in such an engine are specifically claimed.

What I claim is:

1. In a double acting internal combustion 130

- engine, the combination, with a cylinder base having a vertical bore and provided with scavenging air inlet passages and exhaust passages, two cylinders secured in said bore in alignment with each other, a liner within each cylinder, each liner being held to the cylinder base at its inner end and free to expand outward, said liners having inlet and exhaust ports in communication with the corresponding passages in the cylinder base, and a piston movable within the liners, said liners being arranged to form a continuous liner device extending throughout the entire travel of the piston.
2. In a double-acting internal combustion engine, the combination with a cylinder base having a vertical bore and having two sets of scavenging air inlet passages and exhaust passages, and a diaphragm between the two sets of passages, of a pair of cylinders projecting into said vertical bore on opposite sides of the diaphragm and having liners provided with inlet and exhaust ports in communication with the cylinder passages, pistons movable in said cylinders and through the diaphragm, said liners being seated against said diaphragm and having portions extending over the inner surface of the diaphragm to form a running surface for the pistons throughout their movement.
3. In an internal combustion engine, the combination with a cylinder base having a vertical bore and having scavenging air inlet passages and exhaust passages, of a liner extending into said bore and seated on said base and having a shoulder, and a cylinder extending into said bore and seated on said liner shoulder, a clamping ring bearing on the cylinder for clamping the cylinder, liner and base together, a cooling jacket having its outer end secured to the cylinder and its inner open end slidably mounted by a water-tight joint in the clamping ring to provide for expansion and contraction, and passages supplying cooling water to said jacket.
4. In an internal combustion engine, the combination with a cylinder base having a vertical bore and having scavenging air inlet passages and exhaust passages, of a liner extending into said bore and seated on said base and having a shoulder, a cylinder extending into said bore and seated on said liner shoulder, a clamping ring bearing on the cylinder for clamping the cylinder, liner and base together, a cooling jacket having its outer end secured to the cylinder and its inner open end slidably mounted by a water-tight joint in the clamping ring to provide for expansion and contraction, passages supplying cooling water to said jacket, a cooling water chamber in the cylinder base and passages through the cylinder base, liner and cylinder connecting said water chamber with the jacket space for cooling the cylinder base liner and cylinder.
5. In a double-acting internal combustion engine, the combination with a cylinder base having a vertical bore and having two sets of scavenging air inlet passages and exhaust passages and a diaphragm between the two sets of passages, of a pair of cylinders projecting into said vertical bore on opposite sides of the diaphragm and having liners provided with inlet and exhaust ports in communication with the cylinder passages, cooling chambers in the cylinder base, a central transverse water connection from said chambers, and passages extending in opposite directions from said central connection through the liners and cylinder walls to the jackets, for supplying water to cool the liners and cylinders at opposite ends of the engine.
6. The combination, with a cylinder base, a cylinder secured thereto, a liner within the cylinder and a jacket outside the cylinder, said cylinder base and liner having exhaust and scavenging ports, said cylinder base having a chamber for cooling fluid, vertical passages connected to said chamber, and transverse passages in communication with said vertical passages, said liner and cylinder having vertical passages communicating with said transverse passages, and with the space between the cylinder and jacket for circulating cooling fluid through the liner and cylinder to said space.
7. The combination, with a cylinder base, cylinders secured thereto, a liner within each cylinder, and jackets outside the cylinders, said cylinder base and liners having exhaust and scavenging ports, said cylinder base having a chamber for cooling fluid, vertical passages connected to said chamber, and transverse passages in communication with said vertical passages, each liner and its cylinder having vertical passages communicating with said transverse passages, the vertical passages of one liner and cylinder extending in a direction opposite to those of the other liner and cylinder, said vertical passages communicating with the spaces between the respective cylinders and their jackets for circulating cooling fluid through each liner and cylinder to said spaces.
- In testimony whereof, I have hereunto set my hand.

OLAV ESKIL JORGENSEN.
